CLAIM

The ornamental design for a return chute attachment for basketball hoops, substantially as shown and described.

DESCRIPTION

FIG. 1 is a perspective view of a return chute attachment for basketball hoops showing my new design;

FIG. 2 is a right side elevational view thereof;

FIG. 3 is a top plan view thereof, a bottom view being equivalent thereto;

FIG. 4 is a right side elevational view thereof as attached to a basketball hoop shown in broken lines for illustration purposes only;

FIG. 5 is a left side elevational view thereof; and

FIG. 6 is a rear side elevational view thereof.

FIG. 1

FIG. 2

FIG. 3

FIG. 4

FIG. 5

FIG. 6
